US00D955390S

(12) **United States Design Patent** (10) Patent No.: **US D955,390 S**
Zhang et al. (45) Date of Patent: ** Jun. 21, 2022

(54) **RFID HANDHELD SCANNER**

(71) Applicant: **Intermec IP Corporation**, Everett, WA (US)

(72) Inventors: **Yinlei Zhang**, Suzhou (CN); **Yijing Hou**, Guangdong (CN); **Jia Rui Huang**, Shanghai (CN); **Shuming Li**, Shanghai (CN); **Tiecheng Qu**, Suzhou (CN); **Zhao Xia Jin**, Shanghai (CN)

(73) Assignee: **INTERMEC IP CORPORATION**, Everett, WA (US)

(**) Term: **15 Years**

(21) Appl. No.: **29/734,213**

(22) Filed: **May 11, 2020**

(30) **Foreign Application Priority Data**

Nov. 11, 2019 (CN) 201930618259.6

CLAIM

The ornamental design for an RFID handheld scanner, as shown in the accompanying drawings and described above.

DESCRIPTION

FIG. 1 is a first perspective view of an RFID handheld scanner showing a new design;

FIG. 2 is another perspective view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof; and,

FIG. 8 is a bottom plan view thereof.

1 Claim, 8 Drawing Sheets
